UNITED STATES PATENT OFFICE

HERMAN A. BRASSERT, OF CHICAGO, ILLINOIS, ASSIGNOR TO H. A. BRASSERT & COMPANY, OF CHICAGO, ILLINOIS, A CORPORATION OF ILLINOIS

CONSTRUCTION OF HOT BLAST STOVES

Application filed June 19, 1930. Serial No. 462,219.

My invention relates to the construction of hot blast stoves for heating the blast air used in the operation of blast furnaces and has for its special purpose the protection of the hottest zone of the regenerative checkerwork from destruction by excessive temperatures.

Through the recently developed use of washed gas which contains a very low percentage of moisture compared to the gas previously used and the use of more efficient burners, the temperatures in the top section of the checkerwork have been materially raised resulting in the softening and eventual collapse of this part of the checker structure, which up to this time has been made of the same material as the rest of the checkers.

Heretofore the brickwork of the combustion chamber and checkerwork in stoves has consisted of the usual qualities of No. 1 fire brick made of fire clay containing a mixture of silica and alumina in proportions of about $1\frac{1}{4}$ parts of silica to one part of alumina. In some cases No. 2 quality has been used in the lower sections of the stove where high temperatures are not encountered. The No. 1 clay fire brick endure temperatures up to 2200° F. without gradually softening. Until now there has been no need for the use of material having a higher softening point than that of high grade No. 1 fire brick. Silica, alumina and magnesite brick which can resist higher temperatures have not been used on account of their additional cost and on account of their expansion coefficient being at considerable variance with that of fire clay brick.

Stoves have been recently developed which, by means of checker fillers in successive stages, control the velocities of gas and air, thus equalizing the temperature ranges in the checkerwork during a cycle to a far greater extent than was ever accomplished before. All of the zones of the checkerbrick are subjected to a smaller variation in temperature upon reversal of the stove than heretofore. In other words, the temperatures gradient is more uniform at any one zone but it extends to a higher temperature and also a lower temperature as between the top and the bottom because the entire stove

is doing a substantially uniform amount of work. The result of this, as far as the top zone is concerned, is that the ascending cold blast has been heated so high before it enters the top zone that it does not cool off the top zone sufficiently to cause any serious contraction of the brick work. On the other hand, when the stove is reversed on account of the top zone remaining hot during the air blast period, the difference in temperature between the gases of combustion ascending the combustion chamber and striking the top zone of the checkerwork and the checkerbrick is again not sufficient to cause undue expansion. Therefore, the application of brick having a higher fusion point and a higher or different expansion coefficient from the rest of the fire brick used in the walls of the stove and in the checkers below is not objectionable and I have discovered that the use of such brick is now practical and economical.

A further feature of my invention consists in the use of brick especially selected with reference to the characteristics of the dust content of the gas used for combustion in the stove. During the heating portion of the cycle, gases are burned in the hot blast stoves for the heating of such stoves and these gases contain dust of a character dependent upon the source of the gases. If this remaining dust is acid in character I prefer to use silica brick; if it is alkaline in character I prefer to use magnesite brick; and if it is neutral in character I prefer to use alumina brick. It will be understood that my invention includes the use of brick made of any material having a higher softening point than standard No. 1 fire brick, such softening point being high enough to sustain the heat present in the upper portion of the type of stoves referred to above.

It is an object of the present invention to provide a new and improved stove construction in which the brick work at the hottest zone of the regenerative checkerwork is of a character to resist softening at the highest temperatures prevalent at this point.

It is an additional object to provide a construction of this character in which the char-

acteristics of the brick used at the high temperature points are selected in relation to the character of the remaining dust content of the gases used for combustion in the stove.

5 It is an additional object to provide a construction which may be applied to existing stoves without material alteration therein.

Other and further objects will appear as the description proceeds.

10 I have illustrated in the accompanying drawings, one embodiment of the type of stove in connection with which my invention is particularly adapted for use.

In the drawings—

15 Figure 1 is a fragmentary plan view of a portion of the stove;

Figure 2 is a fragmentary view on an enlarged scale showing a section of an intermediate portion of the stove;

20 Figure 3 is a view similar to Figure 2, but showing a lower portion of the stove;

Figure 4 is a fragmentary view showing the supporting construction; and

25 Figure 5 is a schematic vertical elevation showing different types of brick in different vertical sections of the stove.

In the drawings, the walls of the combustion chamber are indicated at 11, the outer stove wall at 12, and the main checkerbrick at 13. These main checkerbrick are generally octagonal in form and have a substantially square passageway 14 extending vertically through the brick. The brick are so placed as to form vertical passageways 15 between them, these passageways being similar in form and design to the passageways 14. These brick 13 are so placed that each horizontal layer breaks joint with the horizontal layers above and below. Thus the vertical passages through the brick also extend in alternate layers between brick.

30 As shown in Figure 5, the upper portion of the checkerwork may consist merely of the main checkerbrick 13. An intermediate section may consist of the checkerbrick 13 together with filler brick 16, some of which may be placed at right angles to each other, as shown in the drawings. A lower section may consist of the brick 13 and enlarged filler brick 17, shown in Figure 2 and Figure 5, and a still lower section may include the checkerbrick 13 and still larger filler brick 18. The bottom construction may include supporting brick 19 and special metal members 20 which latter extend across the vertical passages and serve to support the filler brick.

35 The details of construction of the checkerwork shown form no part of my invention and need not be further discussed.

40 The stove construction shown is one form in which the effective passageway for the gases and air is progressively reduced toward the bottom of the stove so that the temperature at the top of the stove is higher

than that in earlier constructions, as has been set forth in the first part of the specification. My invention is adapted for use in connection with other forms of stove construction in which the same result is secured.

45 The walls 11 of the combustion chamber, which, in this form of construction, is located in the center of the stove, are subjected to high temperatures, but these walls lose some of their heat which passes into the surrounding checkerwork while the uppermost checkerbrick are completely surrounded by other brick and thus reach a higher temperature than even the walls of the combustion chamber.

50 My invention is capable of changes and modification to adapt it to varying conditions and it is to be understood that the construction shown and described is illustrative only and that I contemplate such changes and modifications as come within the spirit and scope of the appended claims.

I claim:

1. In a hot blast stove for the heating of air, said stove being heated by the combustion of a gas having a dust content, a regenerative checkerwork construction having progressively reduced effective passage areas in the lower portions thereof, said construction comprising standard fire brick in the lower portion of the stove and higher temperature resistant refractory brick in the upper portion of the stove, said refractory brick conforming in character to the dust content of the gas used for combustion.

2. In a hot blast stove, a regenerator having progressively reduced effective passage areas in the lower portions thereof, said construction comprising standard fire brick in the lower and middle portion of the checker column and higher temperature resistant brick in the upper portion of the checker column, said higher refractory material having a materially higher alumina content than the standard fire brick used in the lower parts of the checkerwork.

3. In a hot blast stove, a regenerator having progressively reduced effective passage areas in the lower portions thereof; said construction comprising standard fire brick in the lower and middle portion of the checker column and higher temperature resistant brick in the upper portion of the checker column, said higher refractory material containing more than 95% silica.

4. Signed at Chicago, Illinois, this 14th day of June, 1930.

HERMAN A. BRASSERT.
